UNITED STATES PATENT OFFICE.

ARTHUR W. INABINETT AND THOMAS P. DE GAFFERELLY, OF CHARLESTON, SOUTH CAROLINA.

DEFLECTOR FOR OIL-HEATERS.

1,204,984.

Specification of Letters Patent.

Patented Nov. 14, 1916.

Application filed February 29, 1916. Serial No. 81,198.

To all whom it may concern:

Be it known that we, ARTHUR W. INABINETT and THOMAS P. DE GAFFERELLY, citizens of the United States, residing at 5 Charleston, in the county of Charleston and State of South Carolina, have invented certain new and useful Improvements in Deflectors for Oil-Heaters; and we do hereby declare the following to be a full, clear, and 10 exact description of the invention, such as will enable others skilled in the art to which it appertains to make and use the same.

The invention relates to improvements in deflectors for oil heaters.

15 The object of the present invention is to improve the construction of deflectors for heating devices and to provide a simple, practical and comparatively inexpensive deflector adapted to be readily applied to an 20 oil heater and capable of adjustment for throwing downward the heat of an oil heater or analogous heating devices in the desired direction to increase the effect of the heater on persons sitting around the same and to 25 prevent the heat from rising too rapidly to the top of a room.

With these and other objects in view the invention consists in the construction and novel combination and arrangement of parts 30 hereinafter fully described, illustrated in the accompanying drawings and pointed out in the claims hereto appended, it being understood that various changes in the form, proportion and minor details of construction 35 may be resorted to without departing from the spirit or sacrificing any of the advantages of the invention.

In the drawings Figure 1 is a side elevation partly in section of a deflector constructed in accordance with this invention and shown applied to an oil heater, Fig. 2 is a vertical longitudinal sectional view of the deflector, Fig. 3 is a reverse plan view of a portion of the hood of the deflector, 45 Fig. 4 is an enlarged detail view of the means for securing the hood in its adjustment, Fig. 5 is a vertical sectional view of the same, Fig. 6 is a plan view partly in section illustrating the construction of the 50 clamp, Fig. 7 is a sectional view illustrating another form of adjusting means for securing the hood in different positions.

Like numerals of reference designate corresponding parts in the several figures of 55 the drawings.

In the accompanying drawings in which is illustrated the preferred embodiment of the invention, the deflector comprises in its construction a hood 1 designed to be constructed of sheet metal or other suitable material and consisting of a flat top 2 and inclined sides and ends 3 and 4 but the form of the hood may be modified and the interior may have a bright reflecting face or surface. The central or top portion 2 of 60 the hood is secured to an inverted U-shaped supporting member 4^a composed of spaced arms 4^b and a connecting top portion which is riveted or otherwise secured to the said hood. 65

The arms 4^b of the supporting member are pivoted by bolts 6 and 7 to vertical standards 8 and 9 which are suitably secured at their lower ends to a sectional clamp 10 and which are angularly bent near 70 their lower ends to offset the body portions of the standards from the upper portion of an oil heater or other heating device to which the reflector may be applied. The sections of the clamps are substantially semi-circular 75 and have outturned terminals 12 which are pierced by adjusting bolts 13 which securely fasten the clamp around the heater 11 at the top of the lower portion or base but the clamp may be mounted on the heater at any 80 desired point and may be shaped to conform to the configuration of various forms of heaters. 85

One of the arms of the inverted U-shaped support is provided with an extension 14 90 projecting below the adjacent pivot 7 and carrying an adjusting bolt or screw 15 which operates in an arcuate slot 16 and which has a thumb nut 17 for clamping the projecting extension 14 to a bracket 18 in which 95 the arcuate slot is formed. The bracket 18 which is of approximately triangular shape consists of a lower inclined portion 19 and upwardly converging sides 20 and 21 which meet at the upper end of the adjacent 100 standard 9 as clearly illustrated in Fig. 4 of the drawings. The bracket 18 may be fixed to the standard by any suitable means. The arcuate slot extends upwardly 105 from a point adjacent to the lower terminal of the inclined portion 19 of the bracket and when the adjusting bolt is in the lower portion of the arcuate slot, the inverted U-shaped support is arranged in a vertical position. The extension 14 of the support is 110

adapted to swing upwardly to tilt the hood and arrange the same in a rearwardly inclined position for throwing the heat toward the front so that the heating effect of the 5 stove will be increased at the front thereof. The bracket 18 is arranged to permit only a forward adjustment of the extension 14 and it limits the rearward swing of the same. By this arrangement of the bracket a full 10 adjustment of the deflector rearwardly is obtained for throwing the heat forwardly and downwardly.

Instead of providing an adjusting device 15 of the character shown in Figs. 1 to 5 inclusive of the drawings, the inverted U-shaped support may be secured in its adjustment by a pair of friction washers 22 arranged in pairs and interposed between the standard 23 and the arms 24 of the support 20 25. Friction washers of any desired construction may be employed. The washers are preferably secured respectively to the standard and the side of the support and they frictionally engage each other with 25 sufficient resistance to hold the deflector in an inclined position and prevent accidental movement of the hood.

What is claimed is:—

1. The combination with a heater, of a 30 deflector of the class described including a clamp embracing the heater, spaced standards mounted on and extending upwardly from the clamp, a hood and supporting means having sides pivoted to the said standards and adapted to swing to and from a vertical position to permit the hood to be

arranged either horizontally or in an inclined position and means for retaining the hood in its adjustment.

2. The combination with a heater, of a 40 deflector of the class described including a clamp embracing the heater, standards mounted on and rising from the clamp, a hood, an inverted U-shaped support secured to the hood and having its sides extending 45 downwardly from the hood and pivoted to the standards to permit the hood to be arranged either in a horizontal or inclined position, and means for securing the support in its adjustment. 50

3. The combination with a heater, of a deflector including spaced standards, means for mounting the same on the heater, a hood provided with arms pivoted to the standards at the upper ends thereof, one of the 55 arms being provided with an extension projecting below the pivot and an approximately triangular bracket rigidly secured to one of the standards adjacent to the said extension and having an inclined bottom portion provided with an arcuate slot and an 60 adjusting device carried by the said extension and operating in the arcuate slot for securing the hood in its adjustment.

In testimony whereof we affix our signatures 65 in presence of two witnesses.

ARTHUR W. INABINETT.
THOMAS P. DE GAFFERELLY.
